COMBINED NICHE CANDLE AND SHIELD THEREFOR

Frederick D. Lowell, Chicago, Ill.

Application December 13, 1957, Serial No. 48,892

Term of patent 14 years

(Cl. D73—1)

Fig. 1 is a perspective view of a combined niche candle and shield therefor showing my new design;

Fig. 2 is an enlarged side elevational view thereof, showing the profile of the niche candle with its shield in section; and

Fig. 3 is a cross sectional view thereof taken along line 3—3 of Fig. 2.

The essential features of the design reside in the portions shown in solid lines on the drawing.

This application is a continuation-in-part of my application Serial No. D. 44,258, filed on December 19, 1956, and now abandoned.

I claim:

The ornamental design for a combined niche candle and shield therefor, substantially as shown and described.
